CLAIM

What is claimed is the ornamental design for a lighting module, as shown and described.

DESCRIPTION

FIG. 1 is a top, perspective view of a lighting module in accordance with the present design;

FIG. 2 is a bottom perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is a top perspective view thereof, with parts separated.

The even length broken lines immediately adjacent to the shaded areas depict the bounds of the claimed design, while all other even length broken lines are directed to environment. In addition, the dot-dash broken lines illustrate the bounds of the claim. None of the broken lines form part of the claimed design.
